United States Patent Office

Des. 221,571
Patented Aug. 24, 1971

221,571

PLANTER

Lee H. Stevens, P.O. Box 710, Escondido, Calif. 92025

Filed May 11, 1970, Ser. No. 22,926

Term of patent 14 years

Int. Cl. D11—02

U.S. Cl. D35—3

Fig. 1

Fig. 2

Fig. 3

FIG. 1 is a perspective view of a planter, showing my new design;

FIG. 2 is a side elevational view thereof; and

FIG. 3 is a top plan view thereof.

I claim:

The ornamental design for a planter, substantially as shown.
